UNITED STATES PATENT OFFICE.

JULIUS MEYER, OF NEW YORK, N. Y., AND CARL BINDER, OF CHICAGO,
ILLINOIS.

POLE FOR ELECTRIC WIRES.

SPECIFICATION forming part of Letters Patent No. 449,375, dated March 31, 1891.

Application filed October 3, 1890. Serial No. 366,969. (No model.)

To all whom it may concern:

Be it known that we, JULIUS MEYER, of the city, county, and State of New York, and CARL BINDER, of the city of Chicago, county 5 of Cook, and State of Illinois, citizens of the German Empire, have invented certain new and useful Improvements in Poles for Electric Wires, of which the following is a specification.

10 This invention relates to an improved pole for supporting electric wires, such as are used for electric lighting or for supporting the overhead wires of electric railways and for similar purposes; and the invention consists 15 of a pole for electric wires composed of two or more angle-pieces of iron or steel that converge from the base toward the upper end, transverse pieces or plates for connecting the angle-pieces and base plate or shoe, and angle- 20 irons for attaching the lower ends of the converging angle-pieces to the base plate or shoe.

In the accompanying drawings, Figures 1 and 2 represent a front and a side elevation of our improved pole for electric wires, made 25 of two converging angle-pieces. Figs. 3 and 4 are front and side elevations of a modified construction of the same. Fig. 5 is a side elevation of a pole constructed of four converging angle-pieces, and Figs. 6, 7, and 8 are 30 horizontal sections, drawn on a larger scale, showing the connection of the angle-pieces with a base plate or shoe.

Similar letters of reference indicate corresponding parts.

35 Referring to the drawings, A A represent two or more angle-pieces of wrought iron or steel, which are either made straight or slightly curved, and so arranged as to converge from a shoe or base-plate B toward the 40 top end of the pole. For poles of ordinary strength, two converging angle-pieces A are sufficient, while for stronger poles more than two angle-pieces may be used, as shown in Fig. 8. The angle pieces A may be arranged

in any relative position toward each other, 45 provided that the apices of two angle-pieces are in line with the central line of the base plate or shoe B. The converging angle-pieces A are connected either by transverse pieces or lattice-work C, as shown in Fig. 1, or by 50 wrought or cast steel or iron plates C', as shown in Figs. 3 and 5, said pieces or plates being pivoted or bolted to the angle-pieces. The lower ends of the angle-pieces A are attached to the base plate or shoe B by angle-pieces D, which are riveted to the angle-pieces A and the base-plate B, respectively, by means of bolts or rivets. The bottom plate B may be cast or made of wrought iron or steel, or of a block of wood of any suitable size and 60 thickness.

The base plate or shoe B is set into the ground at a suitable depth below the surface of the same and the space between the angle-pieces filled up with masonry or cement. 65

Having thus described my invention, I claim as new and desire to secure by Letters Patent—

A pole for electric wires, composed of two or more angle-pieces of iron or steel that converge from the base toward the upper end, transverse pieces or plates for connecting the angle-pieces, a base plate or shoe, and angle-irons for attaching the lower ends of the converging angle-pieces to the base plate or shoe, 70 substantially as set forth.

In testimony that we claim the foregoing as our invention we have signed our names in presence of two subscribing witnesses.

JULIUS MEYER.
CARL BINDER.

Witnesses for Julius Meyer:

PAUL GOEPEL,
M. REIMHERR.

Witnesses for Carl Binder:

J. B. VAN PATTEN,
T. J. BOLENDER.
